UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL STOVE.

Application filed February 12, 1919. Serial No. 276,536.

To all whom it may concern:

Be it known that I, RUDOLPH HOFFMAN, a citizen of the United States, residing at Kankakee, in the county of Kankakee and 5 State of Illinois, have invented certain new and useful Improvements in Oil Stoves, of which the following is a specification.

The invention relates to oil stoves, and has for its object the provision of improved 10 means for mounting a burner or burners of the stove in operative position.

The object of the invention thus generally stated is obtained by the construction and arrangement illustrated in the drawings, 15 forming part hereof, in which Fig. 1 is a side elevation illustrating one embodiment of the invention. Fig. 2 is an underside plan view of the same. Fig. 3 is a fragmentary, vertical section taken on line 3—3 20 of Fig. 2.

In the drawings, 1 indicates the base of an oil burner having a burner bowl 2 mounted therein, and 3 is a feed pipe for the oil, upon which the burner is supported by 25 the means to be presently described. The feed pipe is in communication with a suitable source of supply (not shown).

For the purpose of establishing communication between the feed pipe and burner 30 bowl, valve-controlled means are usually employed. Herein I utilize such means in mounting the burner upon the pipe, and to this end I provide an angular fitting 4 the lower end of which extends inwardly 35 toward the center of the base and is detachably connected to one side of the pipe 3. At its upper end the fitting has an upright neck portion 5 connected with the burner bowl as by means of solder 6. The fitting 40 is provided with the usual valve member 7 for controlling the flow of oil therethrough.

The means for detachably connecting the lower end of the fitting to the side of the pipe 3 may comprise a shallow cup 8 secured to the pipe by means of a threaded nipple 9, the lower end of the fitting 4 being shaped so as to enter the cup. Preferably a packing ring or gasket 10 is provided between the end of the fitting and the cup, 45 and a rigid clamp device in the form of a yoke 11 having openings 12 therein for receiving the pipe 3, is adapted to cooperate with a set-screw 13 to clamp the lower end 50 of the fitting firmly upon the gasket 10 in

the cup. Said yoke passes around the fitting 55 4, and the clamping screw passes through an opening 14 in the yoke, thence through a bearing member 15 with which it has a threaded engagement, and into a recess 16 in the outer side of the fitting. It will be 60 seen that when the clamping screw 13 is tightened, the burner will be firmly held upon the pipe and especially against tilting circumferentially thereon.

To insure that the burner cannot tilt in 65 a direction lengthwise of the pipe, the base is adapted to engage at substantially diametrically opposite sides with the pipe. To this end the base is provided on opposite sides with two downwardly extending portions 17 each adapted to engage with the pipe so that when the fitting 4 is connected to the pipe by the yoke 11 and the clamping screw 13, the burner will be firmly held 70 against tilting either circumferentially or 75 longitudinally of the pipe. Preferably each of said portions 17 has a rearwardly opening recess or notch 18 therein for the reception of the pipe 3 so that the portions 17 may engage with both the upper and 80 lower sides of the pipe and thus preventing a lifting of the burner off from the pipe and supporting it in case the stove is inverted, as in shipping. It will be apparent 85 that the burner is held in position with the pipe entered in said notches by the means for detachably connecting the burner to the pipe.

It will be seen that I have provided a very 90 practical method of mounting the burner or burners of an oil stove in operative position therein. The construction is very simple and yet effectively accomplishes its purposes. Moreover the parts are so arranged 95 that the burner is located directly above the pipe by which it is normally supported, and by properly proportioning the parts the pipe may be arranged to support the burner and associated parts with the center of gravity thereof substantially vertically 100 above the pipe, thus relieving the connection between the fitting 4 and the pipe 3 from unnecessary strain in carrying the weight of the burner. It will also be apparent that when desired, the burner may be quickly 105 and easily detached from the pipe line without removing or disconnecting the latter from the stove.

I claim as my invention:

1. The combination of an oil burner comprising a base having a burner bowl mounted therein, a feed pipe, and means establishing communication between the burner bowl and the feed pipe, said means comprising a valve controlled fitting having an upright portion rigidly secured to the burner bowl at the forward side thereof and a substantially horizontal portion extending inwardly and rearwardly beneath the burner and detachably secured to the pipe.
2. The combination of an oil burner comprising a base having a burner bowl mounted therein, a feed pipe, and means establishing communication between the burner bowl and the feed pipe, said means comprising a fitting having an upright portion rigidly secured to the burner bowl at the forward side thereof and a substantially horizontal portion extending inwardly and rearwardly beneath the burner and detachably secured to the pipe, said base being adapted to engage at opposite sides with the pipe.
3. The combination of an oil burner comprising a base having a burner bowl mounted therein, a feed pipe, said base having portions on opposite sides provided with recesses for receiving said pipe, and means establishing communication between the burner bowl and feed pipe, said means comprising an upright portion rigidly secured to the burner bowl and a substantially horizontal portion extending inwardly beneath the burner transversely of the feed pipe and detachably secured to the pipe.
4. The combination with an elongated horizontal supporting member, of a burner base having at its opposite sides downwardly extending portions engaging with the upper and lower sides of the supporting member, and a part mounted on the supporting member and detachably connected with one edge of the base to secure the burner in position directly over the supporting member.
5. The combination with an elongated supporting member, of a burner base engaging at its opposite sides with the supporting member, and a member having a portion rigidly secured to the base at one edge thereof and a portion extending inwardly beneath the burner transversely of the supporting member and detachably secured to the support.
6. The combination in an oil stove of a horizontal elongated supporting member, a burner comprising an annular member located directly above and supported by the supporting member, and a clamp device connecting said members arranged beneath the annular member and transversely of the supporting member, said device being adapted to permit of the quick detachment

of the annular member from the supporting member.

7. The combination of an elongated horizontal supporting member, an oil burner comprising a base having at its opposite sides depending portions arranged to engage with said member to support the burner above the member, a yoke member mounted upon the supporting member, a part located at one side of the base and rigid therewith, and means carried by the yoke member and operatively engaging said part on the base whereby to detachably secure the burner upon the supporting member.

8. The combination in a blue-flame wick-less oil stove of a horizontal feed pipe, a burner comprising a burner bowl and an annular member into which said bowl is adapted to fit snugly, said member having its opposite edges adapted to engage the feed pipe, and means beneath the burner providing a connection between the feed pipe and the burner.

9. A supporting means for the burners of oil stoves comprising an annular member into which an annular burner bowl is adapted to fit snugly, said member having depending portions with rearwardly opening notches for receiving the feed pipe of the stove whereby to prevent the burner from tilting on an axis disposed transversely of the feed pipe.

10. In an oil stove, the combination with a horizontal feed pipe, a burner comprising an annular burner bowl, an annular member snugly receiving said bowl and adapted to rest at opposite sides upon the feed pipe, and means establishing communication between the burner bowl and the feed pipe and detachably connecting the burner to the feed pipe, said means comprising a fitting connected to the forward side of the burner bowl and extending rearwardly for connection with the feed pipe, said fitting having a forwardly extending valve member for controlling communication between the bowl and the pipe.

11. In a stove, the combination of a fuel feed pipe, a burner located above and supported by said pipe, and means connecting said pipe and burner comprising a valve controlled fitting connected to one side of the burner, the arrangement being such that the burner is disposed with its vertical axis offset laterally toward the side of the burner opposite the fitting whereby the center of gravity of said burner and fitting is located approximately over said pipe.

In testimony whereof, I have hereunto set my hand.

RUDOLPH HOFFMAN.
